United States Patent Office.

ALFRED BORGNET, OF SWANSEA, ENGLAND.

Letters Patent No. 61,706, dated February 5, 1867.

IMPROVEMENT IN APPARATUS FOR SMELTING ZINC ORES.

The Schedule referred to in these Letters Patent and making part of the same.

TO WHOM IT MAY CONCERN:

Be it known that I, ALFRED BORGNET, of Swansea, England, have invented certain improvements in Furnaces, Retorts, and Apparatus for Smelting or Treating Zinc Ores, and for other purposes; and I hereby declare that the nature of my said invention and the manner in which the same is to be performed are fully described and ascertained in and by the following statement thereof, reference being had to the drawings hereunto annexed, and to the figures and letters marked thereon, that is to say:

My invention of improvements in furnaces, retorts, and apparatus for smelting or treating zinc ores, and for other purposes, consists, first, of a mode of employing two or more fire-grates to each furnace; and, second, of employing retorts, protectors, and heat-regulators having cooling air, vapor, or liquid circulating or passing within them, and by placing them between the said fire-grates and the lowest tier or row of retorts in the furnace; and, third, of employing distilling retorts having special proportions of parts or form, together with, fourth, special forms of and parts in condensing-tubes conjoined with the said distilling retorts; and, further, fifth, in employing tubes for the circulation or passage of cooling air, vapor, or liquid placed on the outside of large retorts or muffles, and in such a position upon them as to be wholly or in part between the furnace fire or the current of heat directed against the retorts or muffles.

The employment of the protectors and heat-regulators, as described, materially assists in preserving the distilling retorts from the destructive action of the heat and in diffusing it throughout the furnace.

The condensing-tubes are made, by preference, the outer one of sheet iron and the inner one of fire-clay. My improvements in the latter-mentioned tube consist, first, of partly closing its end adjoining the distilling retort, as shown in the drawing, by which the liquid metal is prevented from running back into the distilling retort; and, secondly, in forming the upper part of the same end of the tube of an angular shape, by which the condensation of the zinc vapor passing from the distilling retort is greatly facilitated. And my improvement in the outer said condensing sheet-iron tube consists of a low partition or ledge formed across it on its lower side, within, and so as to be near the end of the last-mentioned tube when in position. By this partition or ledge the condensed metal and oxide are kept separate within the said tube.

My improvements in the distilling retorts consist in the proportions of form given to it, first, for obtaining the strength required, and, secondly, for the more equal action of heat upon the ore being distilled within it.

My improvements in the retort protectors and heat-regulators consist in causing cooling currents of air to pass or circulate through them in pipes or tubes or channels. The circulating or passing of air direct from the atmosphere into and through the protectors and tubes will in some cases be occasioned sufficiently by the rarefaction of the air in the said protectors and tubes, producing a natural draught, and this is facilitated by placing one end higher than the other of each protector or tube in the furnace. In other cases it is desirable to force and draw the cooling air, vapor, or liquid through the said protectors or tubes by any convenient mechanical means ordinarily used for such a purpose. The rapidity of the passing of such cooling air, vapor, or liquid should generally be regulated by the workman attending the furnace, according to the amount of heat he may require.

In order to illustrate the application of my said improvements, referred to above, marked 1, 2, 3, 4, I show in the annexed drawings a complete zinc ore furnace in addition to the figures delineating my said invention; and I show that my said invention renders practicable the combination of the chief advantages respectively of the Silesian and the Belgian system of zinc furnaces, resulting in great economy of labor in working the new system and in increased production therefrom. In the said drawings

Figure 1, Sheet I, represents a front elevation of the said furnace.

Figure 1, bis, a longitudinal section of the same at the line A B of

Figure 2, Sheet II, which is a plan thereof.

Figure 3. Sheet III. a transverse section at the line C D of fig. 1; and

Figure 4, a back elevation of it.

Sheet IV, Figures 1, 2, 3, and 4, represents in section and plan the iron-work of the front part of the furnace; and a section and plan of the said new distilling retort, and of the said sheet-iron outer tube; and

Figure 5 shows the form of the said inner clay tube or condenser.

Figure 6, Sheet V, represents the application of the said protectors and heat-regulators for shielding the distilling retorts from the direct action of the fires and for assisting the distribution of heat throughout the furnace.

The retorts, protectors, and heat-regulators, shown in Sheets I, II, III, and IV, and in fig. 6, Sheet V, are by preference composed of a series of fire-clay tubes, open at both ends, and placed within a larger one having a transverse section to the said distilling retort, or a series of fire-clay tubes placed near together without exterior envelope.

Figure 7, Sheet V, shows the application of the principle of my said improved protectors and heat-regulators to the ordinary Silesian zinc retorts or muffles. An open fire-clay pipe or tube or channel is placed from the front thereof along the top and down the back, where it forms a chamber, and thence, by branches along the sides, returns to the front; and

Figure 8, Sheet V, represents one mode of applying the said principle to the protectors used in the Belgian furnaces.

The hole in the back of the said protectors in the Belgian furnaces, being carefully closed, a small clay tube or pipe is placed within it, and reaching nearly to the closed end, serves to conduct a cooling current of air, vapor, or liquid into it, and which can then pass away at the front end thereof.

Having described the nature of my invention and the manner of carrying the same into effect, I do not confine myself to the precise details so long as the principles of the said improvements are retained, and what I claim are the several improvements and combinations herein described.

In testimony whereof I have signed my name to this specification before two subscribing witnesses.

A. BORGNET.
